CLAIM

The ornamental design for an electric washing machine with clothes dryer, as shown and described.

DESCRIPTION

1. Electric washing machine with clothes dryer

1.1 : Perspective

1.2 : Front

1.3 : Back

1.4 : Left

1.5 : Right

1.6 : Top

1.7 : Bottom

1.8 : Front right perspective

1.9 : Front left perspective

1.10 : Front

1.11 : Back

1.12 : Left

1.13 : Right

1.14 : Top

1.15 : Bottom

The broken lines depict portions of the electric washing machine with clothes dryer that form no part of the claimed design; reproduction 1.1 is a front perspective view of the electric washing machine with clothes dryer; reproduction 1.8 is a front right perspective view thereof in a condition that the left and right doors have been opened; reproduction 1.9 is a front left perspective view thereof in a condition that the left and right doors have been opened; reproductions 1.2 and 1.10 are front views of reproductions 1.1 and 1.8, respectively; reproductions 1.3 and 1.11 are back views of reproductions 1.1 and 1.8, respectively; reproductions 1.4 and 1.12 are left views of reproductions 1.1 and 1.8, respectively; reproductions 1.5 and 1.13 are right views of reproductions 1.1 and 1.8, respectively; reproductions 1.6 and 1.14 are top views of reproductions 1.1 and 1.8, and respec-
